United States Patent

Des. 241,329
Patented Sept. 7, 1976

241,329

SELF-PROPELLED VEHICLE

Larry G. Forster, General Delivery, and Bobby Dean
Clark, Lakeside Resort, both of Shoshoni, Wyo. 82649

Filed July 7, 1975, Ser. No. 593,324

Term of patent 14 years

Int. Cl. D12—14

U.S. Cl. D12—85

FIG. 1 is a perspective view of self-propelled vehicle showing our new design;

FIG. 2 is a front elevational view thereof;

FIG. 3 is a top plan view thereof;

FIG. 4 is a rear elevational view thereof;

FIG. 5 is a left side elevational view thereof; and

FIG. 6 is a right side elevational view thereof.

We claim:

The ornamental design for a self-propelled vehicle, as shown.
